UNITED STATES PATENT OFFICE.

JOSEPH S. WYLIE, OF OKLAHOMA CITY, OKLAHOMA.

ROAD-REPAIRING APPARATUS.

Application filed July 7, 1923. Serial No. 650,050.

To all whom it may concern:

Be it known that I, JOSEPH S. WYLIE, a citizen of the United States, residing at Oklahoma City, in the county of Oklahoma and State of Oklahoma, have invented certain new and useful Improvements in Road-Repairing Apparatus, of which the following is a specification.

My invention relates to road-repairing machinery whereby the material for repairing hard surface roads may be readily transported to the point of use and mixed at said point. One object of the invention is to provide novel compact means whereby the several ingredients of the material may be heated before being mixed, and another object of the invention is to provide containers for the several ingredients arranged in compact form and all exposed to a heating element 15 and so arranged that the contents of the several containers may be easily withdrawn in such proportions as may be desired. Another object of the invention is to provide a portable apparatus including a heater, 20 bins or containers for the several ingredients of the road material and a mixer whereby the pre-heated materials may be thoroughly commingled before being deposited upon the road surface. Other objects of the invention will appear incidentally in the course of the following description.

In the accompanying drawings, which illustrate one embodiment of the invention, Figure 1 is a side elevation of my improved apparatus;

Fig. 2 is a plan view thereof partly broken away;

Fig. 3 is a rear elevation, and

Fig. 4 is a transverse section through the heater and parts associated therewith.

In carrying out my invention, I employ a truck consisting of a frame or bed 1 mounted upon rear wheels 2 and front wheels 3, the front wheels being mounted for turning movement whereby the truck may be readily steered. The bed or frame 1 may be of any suitable construction and upon the same, at and adjacent the front end thereof, I erect standards 4 suitably braced and supporting at their upper ends a basket 5 consisting of concave transverse yokes and longitudinal bars 6 connecting the yokes. Supported by the said basket is a mixer 7 which may be of any preferred form and is illustrated as consisting of a suitable casing and a shaft 8 extending longitudinally of

the casing and equipped with paddles 9. At the front end of the mixer is a gate 10 whereby the contents thereof may be withdrawn for use and at the rear end of the mixer a sprocket wheel 11 is secured upon the shaft 8, as shown. A motor 12 is mounted upon the truck adjacent the rear end of the mixer, and this motor may conveniently be an internal combustion engine. Upon the motor shaft is secured a sprocket pinion 13 around which and the sprocket 11 is trained a chain 14 whereby motion may be transmitted from the pinion 13 to the shaft 8 in an obvious manner.

Upon the rear portion of the truck, I erect a casing 15 which is provided internally with longitudinal partitions 16 disposed between its sides and its central longitudinal vertical plane. These partitions terminate short of the bottom of the casing and from their lower edges inclined deflecting bottom plates 17 extend outwardly and downwardly to the bottom of the casing or to the side members or sills of the truck. At the upper ends of the partitions and extending between the front and rear ends of the casing are beams 18 which constitute supports for a kettle 19, the said kettle being substantially U-shaped in transverse section and provided at its upper side edges with lateral flanges 20 resting upon the said beams 18 whereby to be supported in proper position by and between the same. The height of the kettles is less than the vertical extent of the partitions 16 and the sides of the kettle are spaced from the said partitions, as shown most clearly in Fig. 4, an open space being thereby provided between the partitions and the kettle and between the inclined bottom plates 17 for the circulation of heat and products of combustion. A grate 21 is supported in any convenient manner upon the truck between the lower edges of the inclined bottom plates 17, and the rear end of the casing is equipped with a fuel door 22 whereby fuel may be deposited upon the grate and combustion of the fuel regulated. It will be readily noted that the heat rising from a fire kindled upon the grate 21 will play upon the partitions and upon the sides and bottom of the kettle so that the temperature of material placed in the kettle and within the bins or containers defined by the sides of the casing and the partitions will be raised and the material brought into the proper working

condition. The kettle is provided at its rear end with a draw-off spout 23 extending through the rear wall of the casing and equipped with a cut-off valve of any preferred or suitable construction.

Disposed vertically above and spaced from each deflecting bottom plate 17 is a plate 24 which cooperates with the respective deflecting plates 17 to form a discharge spout for the compartment located above it. The plates 17 and 24 may be disposed obliquely longitudinally of the casing, as indicated at 25 in Fig. 1, as well as transversely, as shown in Fig. 4, so that the material passing through the discharge spout thus formed will be directed to an outlet 26 provided in the side wall of the casing. The outlet 26 may be equipped with any suitable controlling door so that the material will be held within the container but may be withdrawn readily as desired. The inner edge of each inclined plate 24 is united integrally or otherwise with the lower edge of an upper transversely inclined plate 27 so that the material gravitating within the container will be deflected toward the inner wall of the same where the heat is greatest before being permitted to flow to the outlet opening. The arrangement of the plates 24 and 27 and their relation to the side walls of the casing provide triangular spaces 28 extending longitudinally of the casing, and within these spaces are disposed flues 29 having their front ends 30 turned laterally so as to open through the partitions 16 at or adjacent the lower edges of the same. The rear ends of these flues project through the rear wall of the casing and are connected directly with upwardly converging branch flues 31 which merge into the outlet flue 32 rising vertically above the top of the casing. The smoke and other products of combustion will thus be caused to pass to the front end of the kettle and then flow laterally into and through the flues 29 by which they will be carried rearwardly and finally discharged through the branch flues 31 and the outlet or escape flue or pipe 32. The heat currents will thus be caused to travel around the entire length of the several bins as well as along the entire bottom of the kettle and will act to raise the temperature of all the parts of the structure. At one side of the casing a single container 33 is provided, and this container is intended to contain broken rock while at the opposite side of the container is arranged a transverse vertical partition 34 near the front end of the casing, thereby defining two compartments 35 and 36 adapted respectively to hold sand and cement, while the kettle 19, of course, is utilized as a container for asphalt. A cover or lid 37 is provided for the entire casing, and this cover may be of any convenient type, being illustrated as having a

depending rim adapted to fit closely around the upper end of the casing whereby the lid will be supported firmly thereon.

At one side of the fuel door 22 a small door 38 is provided so that the tampers and other tools which are employed in repairing asphalt and similar roads may be inserted into the casing over the grate 21 and thereby heated as is desirable.

It is thought the manner of using the apparatus will be readily understood. The road materials are placed in the several compartments of the casing 15 and the fire is kindled upon the grate 21. As the fire will play directly upon the inner walls of all the bins or compartments and upon the entire surface of the kettle, the several ingredients will be very quickly and thoroughly raised in temperature so that they may be easily worked and commingled into the consistency deemed most advantageous for use. When a patch is to be made in the road surface, the ingredients are withdrawn from the several compartments or bins in the proper proportions and are deposited in the mixer 7. The engine 12 is then started so as to operate the mixer and, as a result of the mixing operation, the several ingredients are thoroughly commingled so that they may be readily spread over the worn surface and tamped down in the usual manner. By the use of my apparatus, a single workman may thoroughly repair a considerable stretch of road at a low cost, and it will be readily noted that the apparatus is free from complicated arrangements of elements so that it is not apt to get out of order. The truck may be drawn by draft animals or may be propelled by a motor mounted thereon and serves as a convenient means for transporting the material to the point of use. The apparatus is especially desirable on much traveled roads which require constant attention and will permit a single operator to take care of a long stretch of road in a thoroughly efficient manner.

Having thus described the invention, what is claimed as new is:

1. Apparatus for repairing roads including a truck, a casing mounted upon the truck, partitions within the casing dividing the same into a plurality of compartments, a kettle supported by and between said partitions, means whereby heat may be generated between the partitions to play upon the same and upon the kettle, and means for effecting circulation of the heat through the casing between and at both sides of the partitions.

2. In apparatus for repairing roads, a truck, a casing mounted thereon, longitudinal partitions within the casing, deflecting bottom plates extending downwardly and outwardly from the lower edges of the partitions to the sides of the casing, the

space between the partitions and the sides of the casing constituting containers for road material and the space between the partitions constituting a fire box, a kettle supported between the upper portions of the partitions and in spaced relation thereto, and means for effecting circulation of heat currents about the kettle and past the containers at the sides of the kettle.

3. In road-repairing apparatus, a truck, a casing mounted thereon, longitudinally extending vertical partitions within the casing terminating short of the bottom thereof, downwardly and outwardly inclined deflecting plates extending from the lower edges of the respective partitions to the adjacent sides of the casing, inclined plates disposed above and in spaced relation to the said de-

flecting plates and substantially parallel therewith, upwardly and outwardly inclined plates extending from the inner edges of the second-mentioned inclined plates to the sides of the casing, a kettle supported between the vertical partitions and in spaced relation thereto, a fire-box between and below the first-mentioned inclined plates at the rear of the casing, and smoke flues disposed within the spaces defined by the sides of the casing and the meeting inclined plates, said flues opening at their front ends laterally through the vertical partitions at the front ends of the same and extending at their rear ends through the rear wall of the casing.

In testimony whereof I affix my signature.

JOSEPH S. WYLIE. [L.S.]
